UNITED STATES PATENT OFFICE

PAUL G. PEDDICORD, OF DAYTON, OHIO

DESIGN FOR AN ELECTRIC FOOD SLICER

Application filed April 10, 1933. Serial No. 47,741. Term of patent 14 years.

To all whom it may concern:

Be it known that I, PAUL G. PEDDICORD, a citizen of the United States, residing in the city of Dayton, in the county of Montgomery and State of Ohio, have invented a new, original, and ornamental Design for an Electric Food Slicer, of which the following is a specification, reference being had to the accompanying drawings, forming part thereof.

Figure 1 is a perspective view of the front of the machine, and Figure 2 is a perspective view of the rear of the machine, showing my new design.

I claim:

The ornamental design for an electric food slicer, as shown.

PAUL G. PEDDICORD.
